[57] ABSTRACT

A twin-type slewing crane includes a base rotatably mounted on an upright support which may be posi-

tioned, for example, between two holds of a vessel, and driving means for rotating the base about the support. Two upright columns or masts are mounted on the support adjacent opposite ends of a diameter thereof. Each mast is embraced by an annular bearing each of which pivotally mounts a respective jib or boom for swinging movement in a vertical plane, and respective driving means are associated with each annular bearing to swing the associated boom around the axis of the respective mast. A pair of elevating winches are mounted in axial alignment on the base between the masts, and each connected by cables, trained over pulleys mounted on the associated mast, to the respective booms to raise and lower the booms. A pair of winding winches are also mounted in axial alignment on the base and connected by cables, again trained over pulleys mounted on the associated mast and on the outer end of the associated boom, to lifting hooks or the like. Respective clutch means are provided for each pair of winches so that the elevating winches may be interconnected to operate in synchronism and also the winding winches may be interconnected, to operate in synchronism. Such synchronized operation is utilized when the two booms are swung into substantially parallel relation with each other to act as a twin crane in lifting very heavy loads. Certain of the pulleys may be mounted on a member interconnecting the two masts near the upper ends thereof. In a variant embodiment, the booms are raised and lowered by hydraulic actuators which are connected to sources of hydraulic fluid under pressure through valve means which permit independent operation of each hydraulic actuator, in a parallel arrangement, or synchronized operation of the two hydraulic actuators, connected in series relation.

TWIN-TYPE SLEWING CRANE

BACKGROUND OF THE INVENTION

Prior to this invention, it has been the practice to mount two individual cranes on a common rotatable base so that the cranes may be used singly or in combination depending upon the weight of the cargo to be handled. When the cranes are to be used as a twin crane, the jibs or booms of the two cranes are arranged in parallel relation and operated concurrently, whereby a heavy load may be handled by a force which is twice that of the single crane.

Since each of the two individual cranes is provided with its own winding jib and elevating winches, and also with a swivelling winch, the wiring and piping become extremely complicated and maintenance and inspection become inconvenient and time consuming. In addition, the maintenance of synchronism between the individual cranes, which is most important in the conjoint use of the individual cranes as a twin-type slewing crane, becomes highly complicated and difficult to attain. Therefore, the difficulties involved in conjoint operation of the two cranes as a twin crane become an obstacle to efficient operation of such known twin-type slewing cranes, and they are accordingly less attractive industrially because of the increased costs resulting from such obstacles.

SUMMARY OF THE INVENTION

This invention relates to twin-type slewing cranes and, more particularly, to a twin-type slewing crane free of the disadvantages of prior art twin-type slewing cranes and with which synchronized conjoint operation of two individual cranes, when operating as a twin crane, can be easily attained and maintained.

In accordance with the invention, a common swivel mount or base is rotatably mounted on a mounting base or support on a water-borne vessel, and two upright posts or masts are secured to, or integral with, the common swivel mount to extend upwardly therefrom at diametrically opposite symmetrical locations. A driving means is provided to rotate the swivel mount about its support. Near its lower end, each mast is embraced by an annular bearing which pivotally supports a respective boom or jib for swinging movement in a vertical plane, and respective driving means are operable to swing each boom or jib about its associated mast.

A pair of hoisting winches are mounted on the common swivel mount and are connected by cables, trained over pulleys, to the hoisting hooks or the like of each crane, and a pair of jib elevating winches are also mounted on the common swivel mount and connected by cables, trained over pulleys, to the respective booms or jibs for raising and lowering the same. The two hoisting winches may be interconnected by suitable clutch means for conjoint operation, and the two elevating winches likewise may be interconnected by clutch means for conjoint operation. Preferably, the two hoisting winches are arranged in axial alignment with each other, as are also the two hoisting winches. Thus, the individual cranes may be independently operated both in elevation and in traverse. When an exceptionally heavy load is to be lifted, the two jibs or booms are swung into substantially parallel relation, and the two clutch means are operated to interconnect the two winding winches and to interconnect the two hoisting

winches, whereby the two individual cranes are conjointly operated as a twin-type crane.

Some of the pulleys associated with the cranes may be mounted on a common support interconnecting the two masts adjacent their upper ends. Furthermore, in a variation of the invention, the elevating winches may be replaced by hydraulic actuators each connected between a mast and its associated jib or boom to raise and lower the associated jib or boom. These hydraulic actuators are connected, by suitable selecting valves, to sources of hydraulic fluid under pressure, whereby the hydraulic actuators may be operated independently of each other, in parallel, or conjointly with each other, by being connected in series.

An object of the invention is to provide a twin-type slewing crane free of the disadvantages of the prior art and with which synchronized operation of two individual cranes, with maintenance of synchronism, can be effected easily when the cranes are used as a twin crane.

Another object of the invention is to provide an improved twin-type crane capable of loading and unloading operations with high efficiency in handling cargo ranging from a light load to a heavy load.

A further object of the invention is to provide such a twin-type slewing crane in which the individual cranes are mounted on a common swivel base which is rotatably supported on a suitable mounting means.

A further object of the invention is to provide such a twin-type slewing crane which may be adapted for operation either by mechanical winches or by hydraulic actuators.

For an understanding of the principles of the invention, reference is made to the following description of typical embodiments thereof as illustrated in the accompanying drawings.

BRIEF DESCRIPTION OF THE DRAWINGS

In the drawings:

FIG. 1 is a front elevational view of one form of twin-type slewing crane embodying the invention and illustrating the cranes as arranged for individual operation;

FIG. 2 is a plan view of the crane shown in FIG. 1;

FIG. 3 is a plan view of the crane shown in FIG. 1 as arranged for operation as a twin-type slewing crane;

FIG. 4 is an axial sectional view of the lower portion of the crane shown in FIG. 1, illustrating details of the driving arrangements;

FIG. 5 is a view, similar to FIG. 1, illustrating the crane masts as interconnected adjacent their upper ends;

FIG. 6 is a front elevation view of a twin-type slewing crane forming another embodiment of the invention and in which vertical swinging movement of the booms or jibs is effected by hydraulic actuators; and

FIG. 7 is a hydraulic circuit diagram pertaining to the crane shown in FIG. 6.

DESCRIPTION OF THE PREFERRED EMBODIMENTS

The present invention will be described by way of example hereafter with reference to the accompanying drawings. Referring first to FIGS. 1 to 4, reference numeral 1 designates a common mount or base which is rotatably mounted on a fixed base or support 3 of a

ship, and has two posts or mast 2, and 2' fixedly mounted thereon or integral therewith. The mounting positions of the posts 2 and 2' are diametrically symmetrical with respect to the center of mounting base 3. Reference numerals 4 and 4' designate jibs or booms connected to the respective posts 2 and 2' for swinging motion thereabout. Elevating switches 5 and 5', for elevating the respective jibs 4 and 4', two single crane swinging mechanisms 6 and 6' for swinging the respective jibs 4 and 4' and two winding winches 8 and 8' for moving respective weights or hooks 7 and 7' upwardly and downwardly, are mounted on the common mount or base 1. Mounting base or support 3 is fixed on the hull of the ship between two hatches 9 and 9', and has a turntable bearing 10 provided thereon. The structure on and above the common swivel base 1 is rotatable as a unit, and a rotation mechanism 11 for twin operation, is mounted within the common base 1. Respective annular bearings 12 and 12' embrace posts 2 and 2' for single operation, with the inner race 13 of each bearing 12, 12' being fixed on the respective post 2, 2', while the outer race 14 thereof is integral with a large ring gear 15 meshing with the pinion 16 of the associated swinging mechanism 6 or 6'. A respective jib-mounting housing 23 is secured to each outer race 14, so that the outer race 14 and the associated jib are moved as a unit. With such an arrangement, the upsetting moment is taken entirely by the associated post 2 or 2'.

The arrangement of the respective winches is as shown in FIG. 2. The two winding winches 8, 8' and two jib elevating winches 5, 5' are arranged between the posts 2 and 2' in such a manner that the drums of the respective winding winches are axially aligned as are also the drums of the respective elevating winches. Respective clutches 17, 17' are provided between the winches of each axially aligned pair so that two drums may be coupled together for conjoint synchronized operation.

The wires or cables of winding winches 8, 8' extend into the interior of the associated posts or mast 2, 2' over pulleys 18, 18', at intermediate portions of the posts, and pulleys 19, 19', within the posts, and reach pulleys 21, 21', at the tip ends of the respective jibs, over pulleys 20, 20' at the top ends of the associated posts, to move the associated weights or hooks 7, 7' up and down. The pulleys 20, 20', at the top ends of the posts, and the pulleys 21, 21', at the tips of the jibs, are provided in a plural number, so that the weights 7, 7' may be moved horizontally independently of the vertical movement of the jibs 4, 4'.

The wires or cables of the jib elevating winches 5, 5' extend into interiors centers of the posts 2, 2' through the pulleys 18, 18' and the pulleys 19, 19' and reach the tips of the jibs 4, 4' over the pulleys 20, 20', to swing the jibs 4, 4' up and down. The pulleys 20, 20' at the top ends of the respective posts or mast swivel about the posts 2, 2' following the movements of the associated jibs 4, 4'.

In the present invention constructed as described above, when the single cranes are operated individually, the twin operation swivel mechanism 11 is held inoperative and the clutches for the winding winches 8, 8' and for the jib elevating winches 5, 5' are disconnected, so that the respective winches may be operated individually. In further detail, the hoisting and

lowering of weights 7, 7' are effected by the cables which are led to the winding winches 8, 8' over the pulleys 21, 21' at the tip end of the jibs, the pulleys 20, 20' at the top ends of the posts, the pulleys 19, 19' within the posts and the pulleys 18, 18' at intermediate portions of the posts. The hoisting and lowering of the jibs 4, 4' are effected by the cables which are led to the jib elevating winches 5, 5' over pulleys 20, 20', at the top ends of the posts, pulleys 19, 19' within the posts, and pulleys 18, 18' at intermediate portions of the posts. The jibs 4, 4', as shown in FIG. 2, are swiveled about the posts 2, 2', thereby to effect loading and unloading of cargoes into and from the two hatches 9, 9'.

When the crane is operated as a twin crane, the jibs 4, 4' are positioned in substantially parallel relation as shown in FIG. 3, with the top or outer ends being located at the same level, and clutches 17, 17' are placed in an engaged position. By so doing, it becomes possible to operate winding winches 8, 8' and jib elevating winches 5, 5' in positive synchronism. The hoisting and lowering of weights 7, 7' and jibs 4, 4' are effected in the same manner as in the case of single operation, but the single operation swivel mechanisms 6, 6' are fixed by a brake and all of the structure on above common swivel mount or base 1 is rotated about mounting base or support 3 by means of twin operation swivel mechanism 11.

Since winding winches 8, 8', jib elevating winches 5, 5' and single operation swivel mechanisms 6, 6' are all mounted on common swivel mount 1, the construction is simple and maintenance can be effected advantageously. In addition, the synchronous operation of the single cranes, which is most important in the twin operation, can be attained simply and positively by engaging clutches 17, 17' of winding winches 8, 8' and jib elevating winches 5, 5', and there is no need of a synchronous operation correcting means. Further, since pulleys 20, 20' at the top ends of the posts are rotatable about the respective posts 2, 2', the cables from winding winches 8, 8' and jib elevating winches 5, 5' can be handled smoothly. Still further, since inner race 13 of each single operation swivel bearing 12 is fixed to the associated post 2 or 2', the upsetting moment is taken by said post through pulleys 20, 20' at the top end of the post, so that single operation swivel bearing 12 can be small in size.

The embodiment of the invention shown in FIG. 5 differs from that shown in FIGS. 1 through 4 only in that the masts 2 and 2' are interconnected, adjacent their upper ends, by a common support for the pulleys 18, 18' and 19, 19'.

In the embodiment of the invention shown in FIGS. 6 and 7, hoisting and lowering of jibs 4, 4' are effected by hydraulic actuators 22, 22', instead of by cables and elevating winches. In this arrangement, the correction of synchronism of the jib elevating mechanisms is effected by switching the respective hydraulic circuits from series connection to parallel connection or vice versa. Tandem-type hydraulic pumps 25, 25', driven from an electric motor 24, are individually connected to hydraulic actuators 22, 22' through separate conduits, with control valves 26, 26' and change-over valves 27, 27' being interposed in the respective conduits (see FIG. 7). FIG. 7 shows valves 27, 27' in the state wherein the single cranes are used individually.

When the single cranes are used for the twin operation, changeover valves 27, 27' are shifted, whereby fluid from hydraulic pump 25 enters the hydraulic actuator 22 through control valve 26, and flows from hydraulic actuator 22 through change-over valve 27 to actuator 22. The fluid returns through change-over valve 27' and control valve 26 to hydraulic pump 25. Therefore, the hydraulic actuators 22, 22' make exactly the same stroke. On the other hand, the fluid from the hydraulic pump 25' returns directly to the hydraulic pump 25' through the control valve 26'. The hydraulic parts used in this embodiment are all mounted within the common swivel mount 1, except for the actuators 22, 22'.

In the above-described embodiment, in which hydraulic actuators are used as the jib elevating means, when the individual cranes are used independently twin operation swivel mechanism independently, is held inoperative and clutch 17' of winding winches 8, 8' is disengaged with change-over valves 27, 27' being placed in the positions I in FIG. 7.

The hoisting and lowering of weights 7, 7' are effected by the cables led to winding winches 8, 8' over pulleys 21, 21' at the top ends of the jibs, pulleys 20, 20' at the top ends of the posts, pulleys 19, 19' within the posts and pulleys 18, 18' at intermediate portions of the posts. Hoisting and lowering of the jibs 4, 4' are effected by the hydraulic actuators 22, 22'. Horizontal movement or traverse of jibs 4, 4' is effected by swinging them about the respective posts 2, 2', to load or unload cargoes into or from the two hatches 9, 9'.

On the other hand, when the crane is used as a twin crane, jibs 4, 4' are set in parallel relation, with the top ends thereof located at the same level, and then clutch 17' is engaged and change-over valves 27, 27' are shifted to positions II. By so doing, winding winches 8, 8' and jib elevating hydraulic actuators 22, 22' can be operated in positive synchronization. For swinging the cranes, in this case, single operation swivel mechanisms 6, 6' are fixed by a brake and all of the structure on and above common swivel mount 3 is swiveled about support 3 on the ship hull, by means of the twin operation swivel mechanism 11.

In this embodiment wherein synchronization of the jib elevating mechanism is effected by switching the hydraulic circuits from series connection to parallel connection or vice versa, the synchronous operation, in the use of the crane as twin crane, can also be achieved simply and positively, by the connection of clutch 17', for the two winding winches 8, 8', and the shifting of the change-over valves 27, 27', for the jib elevating hydraulic actuators 22, 22', and there is no need of a synchronous operation correcting means. In addition, since winding winches 8, 8' and single operation swivel mechanisms 6, 6' are mounted on the common swivel mount, and the twin operation swivel mechanism 11 and the jib elevating power means (the electric motor 24, the hydraulic pumps 25, 25', the controlling valves 26, 26' and the change-over valves 27, 27') are also mounted in the common swivel mount 1, the construction is simple and maintenance can be advantageously effected. Furthermore, since actuators 22, 22' are used for the jib elevating mechanism, there is no fear of jibs 4, 4' dropping due to breakage of cables, and further the jackknife phenomenon (the phenomenon in which a warping force acts on the crane in the erected state of the jibs 4, 4') can be avoided.

The preceding illustrations and examples are given merely by way of example, for clear understanding of the nature of the invention and are not intended to unduly limit the scope of this invention, the invention including obvious equivalents and modifications to the extent that such equivalents and modification would be apparent and obvious to the person of skill in this particular art.

What is claimed is:

- 10 1. A twin-type slewing crane comprising, in combination, a common base mounted for rotation about an upright axis; a pair of relatively elongated upright masts supported on said base in spaced parallel relation to each other; respective booms mounted on said masts for swinging movement in their vertical plane and for rotational traverse about the associated mast, each boom supporting a respective hoisting hook for lifting and lowering loads; individually operable hoisting winches on said base each connected by a respective cable to a respective hook; individually operable boom elevating mechanisms on said base each connected to a respective boom to raise and lower the latter; individually operable drive means on said base each
  - 15 operable to rotate a respective boom about its associated mast; driving means operable to rotate said base, together with all of the components mounted thereon, about said upright axis; first coupling means selectively operable to interconnect said winches for conjoint synchronized operation; and second coupling means selectively operable to interconnect said elevating mechanisms for conjoint synchronized operation; whereby said booms and hooks may be operated independently for handling individual loads, or may be operated conjointly as a twin-type crane to hoist a common relatively heavy load.
  - 20 2. A twin-type slewing crane, as claimed in claim 1, in which said boom elevating mechanisms comprise individually operable elevating winches on said base each connected by a respective cable to a respective boom.
  - 25 3. A twin-type slewing crane, as claimed in claim 2, in which said first and second coupling means comprise respective clutches.
  - 30 4. A twin-type slewing crane, as claimed in claim 3, in which said hoisting winches are axially aligned with each other and said elevating winches are axially aligned with each other.
  - 35 5. A twin-type slewing crane, as claimed in claim 2, including pulleys mounted internally of each mast; said cables being craned over said pulleys.
  - 40 6. A twin-type slewing crane, as claimed in claim 2, including a support interconnecting said masts near their upper end; and pulleys on said support; said cables being craned over said pulleys.
  - 45 7. A twin-type slewing crane, as claimed in claim 1, in which said boom elevating mechanisms comprise individually operable hydraulic actuators each connected between a mast and the associated boom; means on said common base providing a supply of hydraulic fluid under pressure; respective lines connecting said last-named means to said actuators; respective control valves interposed in each supply line; and respective selector valves interposed in said supply lines and selectively operable either to connect the associated control valve to the respective hydraulic actuator or to connect both actuators in series with one control valve.

8. A twin-type slewing crane, as claimed in claim 1, including a respective annular bearing embracing each mast adjacent its lower end, the inner race of each bearing being secured to the associated mast and the outer race of each bearing supporting the associated boom; each of said drive means being connected to a respective outer bearing race.

9. A twin-type slewing crane, as claimed in claim 1, including a support rotatably mounting said common base; said driving means including a ring gear secured to said support and a motor mounted on said common base and having an output pinion engaged with said ring gear.
